United States Patent Office.

A. Q. ROSS, OF CLEVES, OHIO.

Letters Patent No. 77,531, dated May 5, 1868.

IMPROVEMENT IN CARRIAGE-STEP SCREEN.

The Schedule referred to in these Letters Patent and making part of the same.

TO ALL WHOM IT MAY CONCERN:

Be it known that I, A. Q. Ross, of Cleves, Hamilton county, State of Ohio, have invented certain new and useful Improvements in Carriage-Step Screens; and do hereby declare that the following is a full, clear, and exact description thereof, reference being made to the accompanying drawings, and to the letters of reference marked thereon.

In the annexed drawings, forming part of this specification—

Figure 1 represents the side of a carriage with the door shut, and

Figure 2 the same with the door open.

A represents the door of the carriage, B the step-screen, which is fastened to the bottom of the carriage, by means of hinges just behind the step C.

This screen B is connected with the door A by means of a bar, D, screwed to the door, and a spring, E, on the screen, with a movable bar, F, from the end of the spring E to the end of the bar D. It operates in such a manner that when the door of the carriage is shut, the bars and spring mentioned hold the screen close to the bottom of the carriage, and when it is opened, the screen falls down, excluding from view, from the opposite side, any person entering the carriage.

The screen can also be operated by a cord, G, fastened to the door, and passing through pulleys H H, through the side and bottom of the carriage, the other end being fastened to the screen.

In this case, when the door is opened, the screen falls down of its own weight, and when it is closed, the cord draws the screen to its place under the bottom of the carriage.

Having thus fully described my invention, what I claim as new, and desire to secure by Letters Patent, is—
The carriage-step screen B, operated by means of bars and spring, or cord and pulleys, or by other equivalent manner, by means of the carriage-door, substantially as and for the purposes above set forth.

A. Q. ROSS.
